UNITED STATES PATENT OFFICE.

GEORGE A. SMITH, OF NEW YORK, N. Y., ASSIGNOR OF SIXTEEN ONE-HUNDRED-AND-FOURTHS TO JAMES W. HENNESSEY, OF NEW YORK, N. Y., FORTY-SIX ONE-HUNDRED-AND-FOURTHS TO ARTHUR LETTS, OF LOS ANGELES, CALIFORNIA, AND TWENTY-ONE ONE-HUNDRED-AND-FOURTHS TO FREDERICK H. WARD, OF BROOKLYN, NEW YORK.

PLATEN-SHIFT MECHANISM FOR TYPE-WRITERS.

No. 910,427.

Specification of Letters Patent.

Patented Jan. 19, 1909.

Application filed December 17, 1906. Serial No. 348,295.

To all whom it may concern.

Be it known that I, GEORGE A. SMITH, a citizen of the United States of America, and a resident of the city, county, and State of New York, have invented certain new and useful Improvements in Platen-Shift Mechanism for Type-Writers, of which the following is a specification.

My invention relates to typewriters and more particularly to platen shifts for typewriters, having among its objects to provide a simplified form of platen shift which possesses all of the positive merits of simplicity, comprising strength, accessibility for and facility of repairing, cleaning, etc., and a decidedly reduced cost of manufacture.

Further, my invention has among its objects to provide an improved system of platen shift levers operating at the rear and beneath the platen which so combines its pivots, levers, and other mechanical parts as to render the machine more easily operated.

With these and other objects in view, my invention consists in a platen shift embodying the improvements in construction and combination of parts hereinafter described and claimed.

In the accompanying drawings illustrating my invention: Figure 1 is a plan view of my improved platen shift. Fig. 2 is a transverse vertical sectional view on line 2-2 of Fig. 1. Fig. 3 is a side elevation of my improved locking device.

Similar characters of reference denote corresponding parts throughout the several views.

1 denotes the frame made in any desired form. Above it is the carriage 2 movable on a rail 3 at the rear of the machine. Shift levers 4, 4^a having keys 5 and 6 respectively on the left and right hand sides extend rearwardly along the sides of the machine, finding a pivot on a longitudinally extending rod 7 near the rear wall of the frame 1. In their intermediate portions, said shift levers are again pivoted at 8 to the slotted vertical arms 9, 9^a, moving with a vertical reciprocating motion on an upper longitudinally extending rod 10, suitably supported in the

sides of the frame. Said vertical arms 9 are each provided with an open vertical slot 11 adapted to allow its movement on said rod 10 and its disengagement from said rod when desired. One of the said vertical arms, 9^a, is pivoted by a screw pivot 33 to a horizontal link 12 securely fastened at its rear-most extremity to a platen shift rod 13 near one end thereof, which is suitably supported in the sides of the frame 1. Said rod 13 is provided at any suitable point, preferably near the center, with an upright rearwardly slanting arm 14 having a forked end 15. Received in said forked end 15 and actuated by the movement of said arm 14, is a platen operating rod 16 carried by downwardly extending links 17; said links being rigid at their upper extremities to a revoluble rod 18 supported in perforations in the sides 19 of the carriage 2. Integral with links 17 and actuated by the movement of said links, and of the rod 18, are forwardly-extending platen-lifting hooks 20 which extend between the sides of the carriage 2 and the platen 21, and engage the platen carrying rod 22. Said platen rod moves with a vertical reciprocating motion in vertical slots 23 in the sides 19 of the carriage 2, and is held within said slots by a removable slide 24 held by a set screw. Carried by the forked arm 14, is a rearwardly extending arm 25 passing beneath and actuating a bichrome ribbon operating rod 26 which allows the use of such a ribbon. Also, securely fastened to said platen shift rod 13, near one side of the frame 1, is an upwardly projecting pin 27. Above said pin 27 and pivoted by a screw 28 to the side of the frame 1, is a rearwardly extending locking arm 29 provided on its lower edge with a notch 30, adapted to be engaged by the pin 27 on the forward movement of the platen shift rod 13 and to thus retain the platen in the upper case position. Said arm 29 is provided at its free end with a horizontal pin 31.

At the left hand side of the frame is an unlocking shift lever 4 operating like the other lever 4^a at the right hand side of the machine already described, and this is ar-

ranged in conjunction with the lever 9. The upper extremity of said lever 9 is pivoted to an arm 32, carrying an unlocking cam 32^a, and movably pivoted on the platen 5 shift rod 13 adjacent to the pin 27 and adapted to be forced beneath the projecting pin 31, raising the arm 29 and causing the disengagement of the pin 27 from the notch 30 whenever the key 5 is depressed. The 10 hub of the cam 32 which surrounds the rod 13 is slotted as indicated at 40, and a pin 41 carried by the shift rod lies in such slot. This arrangement permits the key 6 to be depressed, and the platen shifted and locked 15 by the pin 27 engaging with the latch or locking arm 29, without any movement being communicated to the key 5 and its carrying lever 4. After this disengagement, the cam 32 assumes its normal position on the 20 release of the actuating lever 4, thus allowing the return of the platen to the lower case.

The operation of my improved platen shift is as follows: With the shift levers in 25 the position shown in Fig. 2, by a slight downward pressure on the key 6, at the right hand side of the machine, the shift lever 4^a is lowered, drawing down the vertical arm 9^a until the transverse rod 10 counters the upper wall of the vertical slot 30 11. By this movement the forward extremity of the link 12^a is depressed and as said link 12^a is rigid on the platen shift rod 13, said rod 13 is slightly turned toward the 35 front, similarly actuating the rearwardly slanting forked arm 14, which in turn causes the forward movement of the rod 16. Said rod 16, through its supporting links 17 which are fixed on the revolute rod 18, 40 causes said rod to be partially revolved, and to lift the forwardly extending hooks 20, which in turn elevates the platen carrying rod 22. Through the locking device shown, the platen may be held in this position, until 45 it is desired to use a lower case letter when, by depressing the key 5 the platen will be released. Should it be desirable to use only one capital letter, it is capable of being immediately lowered by a downward pressure 50 on the shift key 5 at the left hand side of the machine which through the arm 32 and pin 41 operates the platen shift rod 13, but at the same time through cam 32^a throws 55 out of operation the platen locking means, allowing the parts to immediately come back to normal position the moment the key is released.

Foremost among the advantages of my invention is its utilization of an improved system of levers and pivots by which the movement of the shift key is transmitted to the platen. Another of the advantages of my improved platen shift is its simplicity, since its combinations of mechanical parts are so

arranged and constructed as to appreciably 65 decrease the number of parts employed. Again, such parts are so arranged as to be more easily operated than those in present use; to be of stronger construction and to be more accessible for cleaning, repairing, etc. 70 Further, by a utilization of rods at the rear and beneath the platen and inclosed in the frame, a more finished appearance is given to the machine through the elimination of the visible forward rods, arms, levers, etc., 75 heretofore so commonly employed in other machines.

Having thus described my invention what I claim as new and desire to secure by Letters-Patent, is:—

1. In a typewriter, the combination of a platen, a platen shift rod actuating said platen, and a means of actuating said platen shift rod consisting of a shift lever, a vertical slotted arm pivoted to said lever, the slot 85 therein being opened at one side, a rod supported in the frame lying in the said slot, and a link connecting said arm and said platen shift rod.

2. In a typewriter, the combination of a 90 platen, a platen shift rod, a revolute rod, an arm carried by the shift rod, a link carried by the revolute rod and adapted to be engaged by the said arm, whereby motion is transmitted from the shift rod to the revolute rod, and hooks carried by the revolute rod for supporting the platen arranged to lift the latter when the platen shift rod is actuated, substantially as set forth.

3. In a typewriter, the combination with a shift rod extending transversely of the typewriter, of a locking means mounted at one end of the said shift rod, the said locking means comprising a notched arm pivoted to the frame and a pin engaging therewith carried by the shift rod, a shift lever at the opposite end for moving the shift rod and operating the locking means, a separate shift lever on the same side of the 105 typewriter as the locking means, and a cam connected with the separate shift lever and operating to release the locking means after it has been set by the first mentioned shift lever.

4. In a typewriter, the combination with a platen, of a platen shift rod, a means of actuating said rod, a forked arm actuated by said rod, a rod actuated by said forked arm, links pivoted to said rod, a revolute 120 rod moving with said links, and hooks moving with said links, said hooks engaging the ends of said platen.

5. In a typewriter, the combination with a platen, of a platen shift rod, a means of actuating said platen shift rod consisting of a shift lever, a vertical arm pivoted to said lever, a link pivoted to the upper extremity

of said lever and pivoted to said platen shift rod, a forked arm actuated by said rod, a rod actuated by said forked arm, links pivoted to said rod, a revoluble rod moving with said links, and hooks moving with said links, said hooks engaging the ends of said platen.

Signed at New York city this 13th day of December 1906.

GEORGE A. SMITH.
